UNITED STATES PATENT OFFICE.

ERNEST COBURN, OF SPOKANE, WASHINGTON, ASSIGNEE TO THE HOLT MANUFACTURING COMPANY, OF STOCKTON, CALIFORNIA, A CORPORATION OF CALIFORNIA.

GRAIN CARRIER.

Application filed June 23, 1920. Serial No. 391,028.

To all whom it may concern:

Be it known that ERNEST COBURN, a citizen of the United States, residing at Spokane, in the county of Spokane and State of Washington, has invented a new and useful Improvement in Grain Carriers, of which the following is a specification.

This invention relates to grain carriers of the endless flexible type, such as are used in threshing machines or separators.

The object of this invention is to produce a durable carrier and one inexpensive to construct.

This I accomplish by dispensing with all materials which are liable to wear out quickly or deteriorate, and instead employ metal channels carried by leather straps, said channels being interlocked in a way to permit the necessary flexibility between adjacent cells.

One form which my invention may assume is exemplified in the following description and illustrated in the accompanying drawings, in which:—

Fig. 1 shows a plan view of a carrier embodying my invention, with a portion of the metallic cells or slats broken away to show the leather straps beneath.

Fig. 2 shows a vertical longitudinal sectional view of the same on an enlarged scale.

Fig. 3 shows a cross-section of one of the cell forming members.

Fig. 4 shows a cross-section of one of the coupling members.

Fig. 5 shows a cross-section of the other coupling member.

As shown in its present form, the carrier is made up of a series of cells, each in the form of a sheet metal channel which includes a bottom web 10, a single flange 11, and a double flange 12. These cell forming members are connected together by inserting the single flange of one into the double flange of the other, the latter flange being bent out at 13 to allow the single flange to rock within whereby to provide the necessary flexibility between adjacent cell members. These cell members are laid down upon leather belts 14, and each is riveted thereon. There are preferably three parallel belts, one at each side and one in the middle, and two diagonally extending belts. The cell members each have a head 15 at each end, such head being formed of an angular piece of metal held in

place by the rivet which attaches the cell member to the outside belt.

The belts at their ends are fastened together to produce an endless carrier by means of two specially formed metallic coupling members, one of which is shown in Fig. 4 and the other in Fig. 5. The member shown in Fig. 4 is in the form of a channel having a single wall 16 and a double wall 17. The single wall 16 is adapted to interlock with the double flange of the adjacent cell member, and the double wall 17 is adapted to receive one end of each of the straps. The other coupling member comprises a U-shaped clip having a straight side 18 and a bent side 19 to receive between them the other end of each belt. The said clip interlocks with the single flange of the adjacent cell forming member and the bent side of said clip permits the necessary flexible movement between the connected parts. The two coupling members are then brought together and fastened by means of bolts 20.

The carrier thus produced possesses great flexibility and is practically indestructible so far as ordinary wear is concerned. The material used is a very light gauge metal and the shapes required are few and easily made so that the completed carrier is much less expensive to build than prior canvas and wood slat carriers.

Various changes in the construction and arrangement of the several parts may be employed without departing from the spirit of my invention as disclosed in the appended claims.

Having thus described my invention, what I claim and desire to secure by Letters Patent is:

1. An endless flexible carrier for grain, comprising a series of transversely extending cells, each formed of a channel-shaped member having a bottom web, a single flange, and a double flange, the single flange being interlocked with the double flange of the adjacent cell and movable to permit the interlocked members to flex, separate metallic end-walls for the cells, and endless flexible straps to which said cell members are connected.

2. An endless flexible carrier for grain, comprising a series of transversely extending cells, each formed of a channel-shaped member having a bottom web, a single

flange, and a double flange, the single flange of one being interlocked with the double flange of the adjacent cell and movable therein to permit the interlocked members 5 to flex, flexible straps to which said cell members are connected, and means for uniting the ends of said straps comprising two metallic coupling members, one in the form of a channel having a single 10 wall and a double wall, the single wall interlocking with the double flange of the adjacent cell member, and the double wall receiving one end of each strap, the other coup-

ling member comprising a U-shaped clip to receive the other end of each strap and to 15 interlock with the single flange of the adjacent cell member, and bolts for uniting said coupling members together, said bolts also passing through the ends of the straps.

In testimony whereof I have hereunto set 20 my hand in the presence of two subscribing witnesses.

ERNEST COBURN.
